(57) **CLAIM**

The ornamental design for an electrode patch for measuring biological information, as shown and described.

DESCRIPTION

FIG. 1 is a first perspective view of an electrode patch for measuring biological information showing our new design;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dashed broken lines in the drawings show portions of the electrode patch for measuring biological information that form no part of the claimed design, and the dash-dot-dash broken lines in the drawings depict the bounds of the claimed design and form no part thereof.
